UNITED STATES PATENT OFFICE.

JACOB CARTUN, OF PHILADELPHIA, PENNSYLVANIA.

VENDING-MACHINE.

1,141,772.

Specification of Letters Patent.

Patented June 1, 1915.

Application filed March 2, 1914. Serial No. 821,919.

To all whom it may concern:

Be it known that I, JACOB CARTUN, a citizen of the United States, and a resident of Philadelphia, in the county of Philadelphia and State of Pennsylvania, have invented 5 a new and Improved Vending-Machine, of which the following is a full, clear, and exact description.

My invention relates generally to vending 10 machines and more particularly is directed to a new and improved construction especially adapted for disposing of newspapers, magazines, pamphlets, and books.

The principal object of my invention is to 15 provide a new and improved machine of the class described having provision for vending different publications, the construction and arrangement being such that the dropping of a coin in an indicated chute closes an electric circuit whereby mechanical means then provides for withdrawing the desired publication and depositing it outside of the machine to be taken away by the purchaser.

A further object of my invention is to 20 provide a machine of the class described adapted to contain a desired amount of different papers, the construction and arrangement being such that the paper desired is selected by the pushing of a designated button after the dropping of a coin in an indicated chute, the mechanical means for actuating the mechanism being interlocking whereby only one paper may be dispensed following 25 the deposit of one coin.

A further object of the invention is to 30 provide a new and improved combination of parts especially adapted for use in vending machines whereby the said parts are brought into desired relation through the dropping of a coin into a chute which closes an electric circuit actuating the said parts, thereby preventing withdrawal of a paper or publication save when the said coin is deposited.

Generally speaking, the object of my invention is to provide a new and improved vending machine especially adapted to dispense newspapers, magazines, pamphlets, and books, the construction and arrangement being such that an improved mechanism of this class is produced and one which will require no personal attention save to renew the supply of papers, the machine disposing of the papers in an efficient manner 55 and in a short space of time.

Other objects and advantages of the invention will appear as the description thereof proceeds, all of which is particularly pointed out and included in the appended claims.

Reference is to be had to the accompanying drawings forming a part of this specification in which similar characters of reference denote corresponding parts in all the views, and in which—

Figure 1 is a perspective view of the machine with the inclosing case in position thereon; Fig. 2 is a front view thereof with the case removed; Fig. 3 is a side view thereof, the casing being shown in section; Fig. 4 is a top plan view, the casing being removed; Fig. 5 is a vertical sectional view showing the mechanism for withdrawing a paper from the supply thereof, and also advancing the supply into suitable position for the next withdrawal; Fig. 5^a is a detail sectional view showing the electrically-actuated means whereby movement of the handle exterior of the machine actuates the mechanism only when the circuit through the said electrical means is closed; Fig. 6 is a view of a newspaper showing the bar of magnetic material thereon; Fig. 7 is a vertical sectional view showing the details of the coin-controlled circuit-closing device; Fig. 8 is a diagrammatic view setting forth the wiring used in the machine; Fig. 9 is a side view of two of the selector rods showing the interlocking means; Fig. 10 is a front view of an insulated base having a number of contact points thereon; Fig. 11 is a vertical sectional view of this base showing the means whereby certain of the contact points are placed in circuit with another one through the action of the selector rods, shown in Fig. 9; Fig. 12 is a detail view of the circuit closing device which is actuated when any one supply of papers is exhausted; Fig. 13 is a plan view of this device; Fig. 14 is a vertical sectional view thereof on the line 14—14 of Fig. 12.

Generally speaking, the operating means of my machine is positioned on any suitable stand or support 1, the whole being designed to be inclosed by a casing 2, the casing being provided with an opening 3 in its front side whereby a movable handle 4 may extend exteriorly of the actuating mechanism. The front of this case is further provided with suitable openings 5, behind which a

110

signal is adapted to be displayed when any one supply of papers is exhausted; a plurality of openings 6, adapted to receive a coin of certain value is also provided. Also 5 extending exteriorly of the machine, and in convenient position for actuation when the handle 4 is actuated, are the selector rods 7, 7^a, having enlarged heads or buttons 8, 8^a, at their ends whereby the purchaser makes 10 the selection of the paper desired. The top of the support 1 (Fig. 4) is provided with a plurality of openings 9, 9^a, through each of which a paper is adapted to be dropped onto suitable guides 10 after the device has been 15 actuated; there will be as many openings in the top of the stand 1 as there are different publications contained within the machine, the dimensions of the supporting member and casing being determined thereby, the 20 guides 10, however, being so arranged beneath the top of the support 1 that a paper dropping out of any one of the openings 9, 9^a, comes to rest at the bottom of these guides and against the upturned ends 25 11 thereon.

Referring particularly to Fig. 4 the top of the support 1 is provided with suitable bearings 12 within which the frame 13 is adapted to travel, the frame being provided 30 with a plurality of cross arms 14, 14^a at the center of which an electro-magnet 15, 15^a, or a plurality thereof is secured. This frame 13 is adapted to be reciprocated back and forth within the bearings 12, always 35 moving between the same limits, it being noted particularly that the electro-magnets 15, 15^a, are positioned closely adjacent and above the openings 9, 9^a, in the top of the support through which the papers are 40 dropped. Of course the length of the frame 13 and the number of cross arms with electro-magnets thereon will be determined by the number of different publications to be contained within the machine, the device 45 which I have selected for description and illustration being one that is adapted to dispose of two different papers; the principle of operation and the inventive idea involved is present in a machine adapted to vend any 50 practicable number of publications, the construction and operation, however, being amply set forth in the machine described. Secured intermediate of the width of the top of the supporting member 1 are the supports 16, 16^a, across each of which a number 55 of papers are adapted to be positioned in succession, a number thereof being maintained in upright position by engagement with the movable rack 17, 17^a, against which the last paper rests. Since the construction and operation of each of the racks 17, is 60 preferably identical, one only of them will be described; extending transversely of the rear end of the supports 16 and mounted in suitable bearings therein is a shaft 18 hav-

ing a pinion 19 thereon around which a chain 20 passes; adjacent the front of the supports 16 and extending transversely of the machine is a shaft 21 having a pinion 22 thereon, the before-mentioned chain 20 also 70 passing around this pinion. The shaft 21 is supported in suitable bearings 23 adjacent its ends and a bevel gear 24 is carried by the right hand end of this shaft.

Referring particularly to Fig. 5 it will be 75 noted that the chain 20, at some convenient point in its length, is provided with an offset pin or lug 25. The bottom member 26 of the rack 17, which member engages in suitable channels 27, within the adjacent 80 faces of the supports 16, is provided with a downwardly extending arm 28 in engagement with this pin 25 whereby as the chain 20 is moved toward the left, the rack 17 will be moved in the same direction, therebv 85 carrying the stack of papers 29 in the same direction. Extending across the machine and at a suitable distance from the front is a shaft 30 suitably mounted in bearings 31 adjacent its opposite ends, the shaft being 90 provided with a wheel 32 intermediate of its length, the wheel being provided with a number of serrations 33, substantially as shown in Fig. 5. One end of the shaft 30 is provided with a bevel gear 34; extending longitudinally of the right hand side of the machine is a shaft 35 having a number of bevel gears 36, 36^a, freely rotatable thereon, the gear 36 meshing with the gear 24 at the 95 end of the shaft 21, previously mentioned, (Fig. 4), the gear 36^a meshing with a similar gear at the end of a similar shaft but operating in connection with a different rack holding different papers. The face of each hub of each of the bevel bears 36, 36^a, is notched as at 37, 37^a, the shaft being provided with movable clutches 38, 38^a, thereon adapted to be actuated by certain means, thereby coming into engagement with the notched faces 37, 37^a, whereby the turning 100 of the shaft 35 is imparted to either the shaft 21 or others performing a like function. Turning of the shaft 30 (Fig. 4) is imparted to the longitudinally extending shaft 35 by means of the bevel gear 34 at the end of the shaft 30 and a similar gear 39 fixed on this shaft 35; thus it will be seen that turning of the shaft 30 always turns the shaft 35, the shaft 21, however, or others performing a similar function being turned only through bringing the clutches 38 or 38^a into play, it being possible by 105 means to be later described to actuate only one clutch at the same time.

The selection of the desired paper is effected by pushing inwardly on either of the buttons 8 or 8^a, thereby actuating either of the selector rods 7 or 7^a, each of these rods being suitably mounted in supports 40, the buttons on the outer ends of the rods being 110 115 120 125 130

5 maintained in normal position through the medium of helical springs 41 surrounding each rod and bearing against each support and an adjustable collar 42 respectively carried thereby.

Referring particularly to Fig. 3 it will be noted that each of the clutches 38, 38^a is provided with an annular recess 38', 38^b, the push rod 7 being provided with an adjustable offset end 43 engaging in the annular recess 38' while the adjustably mounted arm 43' on the selector rod 7^a engages in the annular recess 38^b in the clutch 38^a. It will be noted that pushing inwardly on either button 8 or 8^a will move either selector rod 7, 7^a, thereby bringing either clutch 38, 38^a, into engagement with either notched face 37, 37^a, whereby the supply of papers from which one is desired is pushed forwardly; in order to prevent pushing inwardly on both buttons 8, 8^a, at the same time in an attempt to obtain more than one paper after inserting a single coin I provide a locking means, shown particularly in Fig. 9. Pivotaly mounted at 44 to a suitable rigid support is a lever having arms 45^a, 45^b, each rod 7, 7^a, being provided with a transversely extending pin 46^a, 46^b, each pin being closely adjacent the opposite ends of the lever; by pushing inwardly, say, on the button 8, the pin 46^b will be brought into engagement with the end 45^b of the lever, thereby swinging the lower end 45^a of the lever toward the front when the offset arm 43 on this rod 35 is actuated, the clutch 38 thereby serving to turn the shaft 21 when the shaft 35 is turned; this moving forwardly of the lower end 45^a of the lever prevents the button 8^a being pushed inwardly since, in order to bring the clutch 38^a into engagement with the serrated face of the gear 36^a, in order to actuate the shaft similar in function to 21, it is necessary that the pin 46^a be pushed rearwardly a certain distance, this pushing being prevented by reason of the engagement of the pin with the arm 45^a which has been moved forwardly.

In order to actuate the shaft 30, thereby actuating the longitudinally extending shaft 35 whereby the supply of papers is moved forwardly and also to reciprocate the frame 13, I make use of means preferably of the following construction. Referring particularly to Figs. 5 and 5^a, a forked arm 47 55 is freely mounted on the shaft 30, the arms of the fork being positioned adjacent opposite sides of the serrated wheel 32, the handle 4 forming part of this forked arm and extending exteriorly of the machine. Pivotaly secured at 48 and preferably on opposite sides of the forked arm 47 is the lever 49 having a hooked lower end 50, the upper end of the lever being provided with a suitable pin or equivalent device 51 to which 60 is attached a chain or cord 52, the other end

of which engages a hook 53 secured to the cross arm 14^a of the frame 13; the forked lower end 50 of this lever 49 is adapted to engage a fixed pin 54 extending laterally of the forked arm whereby after the handle 4 70 is moved downwardly a certain distance the pin or pins 54 will engage the end of the lever, thereby moving it and also the chain 52, whereby the frame 13 is also moved. Extending upwardly from the forked arm 47 75 is a support 55 having an electro-magnet 56 at its upper end adapted to be actuated through the closing of an electric circuit by the deposit of a coin which is to be later described. Pivotaly secured on the forked arm is a lever 57 carrying an armature 58 at its upper end, the lower end of this lever forming a pawl 59 which is adapted to engage in any one of the teeth 33 on the periphery of the wheel 32.

Referring particularly to Figs. 5 and 6, it is to be noted that a piece of magnetic material 60, such as iron, is positioned in each of the papers in the stack 29, the magnetic material lying closely adjacent and in line 80 with the poles of the electro-magnets 15, 15^a, mounted on the frame 13; when the circuit through the electro-magnets 15, 15^a is closed, movement of the frame 13 will carry these electro-magnets toward the front of the machine, also carrying one paper or publication from each of the stacks 29, the movement of the frame being such that the paper is carried sufficiently apart from the stack so that, when the circuit through the electro-magnet is opened, the paper will drop of its own weight through any of the openings 9, 9^a, in the top of the support or stand 1.

While the actual operation of selecting the paper desired and the withdrawing of a 105 copy thereof from the stack is accomplished by mechanical means, the parts are brought into relative operative position by suitable electric circuits adapted to be closed through the deposit of a coin, these circuits 110 being substantially as follows. Referring particularly to Figs. 7 and 8, a plurality of chutes 61, the number of which will depend on the number of different publications to be vended, are provided adjacent the front 115 of the machine, the upper end of each chute terminating in the openings 6 in the front of the casing previously mentioned. Adjacent the bottom of the chutes is a support 62 preferably of insulating material, there being a movable rod 63 mounted in suitable bearings 64 on this support, the rod being maintained in normal position by means of a helical spring 65 carried thereby. Adjustably secured on the upper face of the 120 rod 63 are a number of contacts 66, the free end of each of which extends for a suitable distance across the bottom of the chute and adapted to contact with a suitable coin 67 dropped into the chute. One end of the 130

movable rod 63 is provided with a down-turned portion 68 lying in the path of a movable lever to be subsequently set forth. Each of the chutes 61 is in electrical connection with one side of a suitable battery 69, the movable rod 63 with the contacts 66 thereon being connected to the other side of this battery, the electro-magnet 56 carried by the forked arm 47 being in series there-with so that when the coin 67 is dropped into the chute it completes the circuit through this electro-magnet whereby it is energized and the armature 58 at the upper end of the lever 57 is moved adjacent the poles thereof, the lower or pawl end 59 of this lever being thereby brought into engagement with one of the teeth 33 on the wheel 32; if the handle 4 is now moved downwardly, the shaft 30 will be turned because of the engagement between the pawl 59 and the teeth on the wheel 32 carried by this shaft, the turning thereof being imparted to the longitudinally extending shaft 35 at the side of the machine through the medium of the bevel gears 34 and 39. It is clear that if no coin has been deposited in either of the chutes 61 that the circuit through the electro-magnet 56 is open so that movement of the handle 4 will not turn the shaft 30, thereby preventing movement of other parts of the device with the consequent withdrawal of any paper. This deposit of the coin with the actuation of the armature 58 is the first step in the operation of the machine; in order to transmit turning movement of the longitudinally extending shaft 35 to any of the transversely extending shafts 21 it is necessary to move either selector rod 7 or 7^a in order to complete the circuit between either electro-magnet 15 or 15^a and also to bring the movable clutch 38, 38^a into operation, the paper desired being then withdrawn.

Referring particularly to Figs. 4, 8, 10, 11, it will be noted that each of the selector rods 7, 7^a, is provided with a suitable adjustable support 70 carrying an insulated arm 71 at one end, the arm being provided on its inner face with a short helical spring 72; directly in rear of each of the insulated arms 71 is an insulated support 73 having a plurality of studs or contact points 74, 75, 74', 75', thereon, each pair 74, 75, or 74', 75', being adapted to be placed in electrical connection through the movement of either helical spring 72 thereagainst, this movement being effected by pushing inwardly on either selector rod. The electro-magnet 15 carried on the frame 13 is connected in series with the contact point 74, 75, and the battery 69; the electro-magnet 15^a also carried by the movable frame 13 is in series with the contact point 74', 75' and this same battery. After the coin has been deposited in either chute, thereby closing the circuit with the

electro-magnet 56, pushing inwardly on either selector rod 7 or 7^a will close the circuit through either electro-magnet 15 or 15^a and at the same time will bring either movable clutch 38, or 38^a into operation whereby the proper stack of papers is moved and one is withdrawn therefrom by reason of the field of force set up by the poles of the electro-magnet and acting on the strip or piece of magnetic material positioned in each paper; it is to be noted from Fig. 8 that each of the pair of contacts 74, 75, or 74', 75', is in series with each of the chutes 61 so that, even though either selector rod be operated and the handle 4 be also moved, no paper will be withdrawn for the reason that it is necessary to insert the coin 67 in order to close the electric circuit through any of the electro-magnets.

In order to insure the dropping of the coin out of the chute after a paper has been vended I make use of the structure shown particularly in Figs. 2, 5, and 7, this construction being substantially as follows. Pivotedly secured in position at 76 is the lever 77, one end of which lies directly in the path of the downturned portion 68 of the movable rod 63 adjacent the lower ends of the chutes, the other end of this lever lying directly in the path of the forked arm 47; after the coin has been deposited and the handle 4 has been moved downwardly, thereby operating the machine and withdrawing the desired paper, the forked arm 47 comes into engagement with the lower end of this lever 77, thereby moving its upper end into engagement with the downturned portion 68, before mentioned, which brings the movable rod 63 to the right, (Fig. 7) thereby permitting the coin 67 to drop into a suitable receptacle 78; the handle 4 being released, the leaf spring 79 will bring it back into normal position, the helical spring 65 positioned on the movable rod 63 bringing this rod back into normal position, dropping of the coin into the receptacle thereby opening circuits and preventing the withdrawal of any more papers until another coin has been deposited in the desired chute.

It is desirable that some means of indicating the exhaustion of a supply of some paper be used and to this end I provide certain means shown in Figs. 5 and 8 and in detail in Figs. 12 to 14. Suitably secured to the top of the stand and intermediate of the supports 16, 16^a, is an insulated member 80, having a pivoted lever 81 thereon, the lower end of which is provided with a contacting element 82 insulated therefrom, one end of this element being in contact with a block or stud 83; suitably positioned in the rear of the other end of the contacting element 82 and carried by the insulating member 80 is a contacting point 84 which when the upper end of the lever 81 is moved

forwardly is placed in circuit with the block or stud 83 through the medium of the contacting element 82 which engages therewith. Movement of the upper end of the lever 81 is effected in the following way. Extending rearwardly from each of the movable racks 17, 17^a is a suitable support 85, having a fixed member 86 thereon, there being a pivoted lever 87 carried by this member and movable relatively thereto, the position of the lever, however, being maintained in the same plane as the fixed member through the medium of a leaf spring 88 bearing thereagainst. As either of the racks 17, 17^a moves sufficiently forward so that the last paper in the front thereof has been dropped to either of the openings 9, 9^a, this pivoted lever 87 will come into engagement with the upper end of the lever 81, thereby moving the contacting element 82 to the rear and bringing it into contact with the point 84, thereby closing a suitable circuit, shown diagrammatically in Fig. 8. Contained within the case and adjacent the front thereof are a suitable number of indicating devices which may be of any desired form and preferably are annunciator drops, (as shown particularly in Fig. 3) each of which is in circuit with the contacting elements just described whereby, when either supply of papers is exhausted, the circuit will be closed through the said drops, thereby causing the signal to be displayed, as shown particularly in Fig. 1. Since I have illustrated a machine capable of vending two different publications I have shown (Fig. 2) two separate drops 89, 90, the drop 89 being in series with the contacting points 83, 84, and also with the battery 69; the other drop 90 is in circuit with the contacting points similar to 83, 84, but which are adapted to be actuated by a second movable rack, only one being set forth specifically since the construction of both is substantially the same.

It will be noted that the successive forward movements of each of the racks 17, 17^a, is determined by the angle through which the handle 4 extending on the outside of the machine moves, this movement being effected through the engagement of the pawl 59 with the teeth 33 on the wheel 32; it is clear that the greater the angle through which this handle 4 moves the greater will be the movement of these racks and, in order to adapt the device to the vending of papers of different thicknesses, I provide the means shown particularly in Fig. 2. Adjacent the front of the machine and inside of the casing is a support 91 having guides 92 on the rear side thereof, there being a notched plate 93 movable within these guides; extending forwardly from and in pivotal engagement with this plate 93 is a handle lever 94 whereby movement of the upper end thereof will move the plate 93

in either direction within certain limits. The lower edge of this plate 93 is provided with a plurality of notches 95, 96, 97, of increasing depth, the inner end of the handle 4 when in normal position engaging the lower edge of this plate and entering either one of these notches. As shown particularly in Fig. 2, the handle is positioned within the notch 95 of least depth, such positioning providing for the minimum amount of forward travel of the racks 17, 17^a, the depth of this notch being determined with reference to papers of small thickness; in the event of the machine vending papers made up of a large number of sections, such as the Sunday editions, the handle 94 would be moved to the right, thereby moving the notch 97 of greatest depth directly over the handle 4 and into engagement therewith and thereby providing for a greater angle of swing of the handle 4 with the consequent greater travel of the racks and the frame.

The operation of my machine may be summed up briefly as follows. The papers are placed in position on the racks, each rack being moved to suitable position by turning either the shaft 21 or others similar to it, each shaft being preferably provided at one end with suitable pins adapted to coöperate with a wrench or key whereby the turning is made easy. The handle 94 is brought to such position that the proper notch in the plate 93 lies over the exteriorly extending handle 4 when the machine is in position for use. By dropping a coin into either chute 6 the person desiring a paper makes his selection, dropping of this coin closing the circuit through the magnet 56, thereby bringing the pawl 59 into engagement with the teeth 33 on the wheel 32; by then pushing inwardly on either selector rod 7 or 7^a the contacts 74, 75, or 74', 75' are brought into circuit with each other whereby either magnet 15 or 15^a is energized, a downward movement on the handle 4 then actuating the machine and withdrawing a paper which falls down on the guides 10, held in position thereon by reason of the upturned ends 11. The handle 4 is then released, the spring 79 bringing it back to normal position, either of the rods 7 or 7^a being returned to normal position through the helical springs 41 (Fig. 3). After the handle 4 has been moved downwardly a certain distance it comes into engagement with one end of the lever 77 whereby the movable rod 63 (Fig. 7) is moved to the right, thereby permitting the coin 67 to drop into the receptacle 78, the circuits being thereby opened and the machine in position to receive another coin in order to withdraw another paper. As the papers are successively withdrawn and after the final one has been withdrawn, the pivoted lever 81 (Fig. 14) is actuated by the lever 87 carried by the rack whereby the cir-

cuit between the contacts 83, 84, (Fig. 5) is closed, through either of the signals or annunciator drops 89 or 90, thereby giving notice that a certain supply of papers is exhausted.

5 From the above description, taken in connection with the accompanying drawings, it will be observed that I employ mechanical means in the actuation of the device, the 10 mechanical means being electrically controlled through the closing of circuits brought about by the dropping of a coin; the particular form of many of the parts shown is not of essential importance, the 15 idea and the spirit of the invention residing in coöperation with the parts whereby a certain new and useful result is obtained. Many of the elements and many of the parts of the machine may be variously changed as 20 to form and size and it may be advantageous in some cases to make many of the parts adjustable in order to provide a machine of standard make adapted to take care of the vending of papers of different sizes as well 25 as thicknesses.

Having thus described my invention, I claim as new, and desire to secure by Letters Patent:—

1. A vending machine comprising means 30 for supporting a number of papers in position, means whereby to render each paper magnetically attractable, and means for withdrawing each of the papers successively, the said withdrawing means being in the 35 form of electrically energized devices for attracting the papers and placed in circuit through the dropping of a coin.

2. A vending machine comprising means 40 for supporting a number of papers in position, means whereby to render each paper magnetically attractable, and means for successively withdrawing a single paper, said withdrawing means comprising electro- 45 magnets in circuit with a suitable battery and directly acting upon each paper, the circuit being coin-controlled.

3. A vending machine having means for supporting a number of papers in position, a piece of magnetic material in each paper, 50 and means involving an electro-magnet for successively withdrawing single papers, the circuit containing the electro-magnet being coin-controlled.

4. A vending machine comprising means 55 for supporting a number of papers in position, each paper containing a piece of magnetic material, and a coin-controlled magnet movable relatively to the papers and adapted to withdraw them successively when the magnet is moved successively relative to the said 60 papers.

5. A vending machine comprising means for supporting a number of papers in position, a piece of magnetic material in each 65 paper, a magnet adapted to coöperate with

the magnetic material in each paper successively, means for moving the magnet in order to withdraw the paper, and coin-controlled means for closing the circuit through the said magnet.

6. A vending machine comprising means for supporting a number of papers in position, each paper containing a piece of magnetic material, a magnet in circuit with a suitable battery adapted to coöperate with the magnetic material in each paper successively in order to withdraw them, means for moving the magnet and coin-controlled means for closing the circuit through the said magnet.

7. A vending machine comprising means for supporting a number of papers in position, each paper containing a piece of magnetic material, a magnet adapted to coöperate with each piece of magnetic material successively in order to withdraw the papers, a frame on which the magnet is mounted, means for moving the frame and a coin-controlled electric circuit connected to the said magnet whereby, when the circuit is closed and the frame is moved, the papers may be successively withdrawn.

8. A vending machine comprising means for supporting a number of papers in position, a piece of magnetic material in each paper, movable means comprising a magnet, operation of which successively withdraws the papers from the said supply, coin-controlled means for closing the circuit through the said magnet, and mechanical means for moving the magnet and with it one of the papers.

9. A vending machine comprising means for supporting a number of papers in position, a piece of magnetic material in each paper, an electro-magnet, a suitable battery in circuit therewith, coin-controlled means for closing the circuit through the magnet, mechanical means for moving the magnet when the circuit has been closed in order to successively withdraw a paper, and other means for moving the supply of papers adjacent the magnet as the number of the papers becomes less.

10. In a vending machine adapted to contain a quantity of papers to be successively disposed of, the combination of a number of pieces of magnetic material positioned in the papers with an electro-magnet in circuit with a coin-controlled device for closing the circuit, the electro-magnet being movable relatively to the papers and the poles thereof co-operating with each successive piece of magnetic material in order to successively withdraw one of the papers.

11. In a vending machine adapted to contain a quantity of papers, a shaft, a wheel having a notched periphery secured to the shaft, a handle freely rotatable adjacent the wheel, the handle being in operative relation

with a pivoted pawl, and coin-controlled magnetic means for moving the pawl into engagement with the notched periphery of the wheel whereby movement of the handle will 5 move the shaft, thereby actuating certain of the devices in the machine.

12. In a vending machine adapted to contain a quantity of papers, a shaft adapted to actuate some of the devices in the said machine, a wheel having a notched periphery secured to the shaft, a handle movably mounted adjacent the wheel, a pawl carried by the handle, an electro-magnet adapted to move the pawl into engagement with the 15 wheel, and a coin-controlled electric circuit co-operating with the said magnet, whereby movement of the handle will turn the shaft, the opening of the circuit bringing the pawl out of engagement with any one of the 20 notches, thereby preventing turning of the shaft by movement of the handle.

13. In a vending machine, the combination of a shaft adapted to actuate certain of the devices therein, a wheel having a notched 25 periphery secured to the shaft, a handle freely rotatable adjacent the wheel, a lever pivotally supported on the handle, one end of the lever forming a pawl, the other end of the lever being provided with an armature, 30 an electro-magnet carried by the handle adjacent the armature, and coin-controlled means for closing the circuit through the electro-magnet in order to bring the armature adjacent thereto and the pawl into engagement with any one of the notches whereby 35 movement of the handle will move the shaft.

14. In a vending machine, the combination of a number of papers each containing a 40 piece of magnetic material, a movable element having an electro-magnet thereon adapted to successively withdraw one of the said papers, a shaft co-operating with other means in order to move the supply of papers 45 adjacent the magnet as the number thereof is decreased, a handle extending exteriorly of the machine and adapted to actuate the said shaft, together with coin-controlled electro-magnetic means for placing the handle 50 in operative relation with the said shaft.

15. A vending machine comprising means for holding a number of papers in position, each paper containing a piece of magnetic material, a movable element carrying an 55 electro-magnet, the poles of the magnet being adjacent the magnetic material in the papers, a shaft, means between the shaft and the papers for moving them forwardly as each one is successively withdrawn, a 60 handle freely mounted adjacent the shaft, means between the handle and the said element whereby movement of the handle will move the element, and a pawl carried by the handle and adapted to be brought into engagement with elements carried by the shaft 65

by the dropping of a coin whereby movement of the handle will also move the papers forwardly.

16. In a vending machine, a rack for holding a number of papers in position 70 therein, each paper containing a piece of magnetic material, a shaft in operative relation with the said rack for moving it forwardly as the papers are withdrawn, a wheel on the shaft, notches on the wheel, a handle freely mounted adjacent the wheel, a movable frame in operative relation with the handle, the frame being provided with a magnet for co-operating with the magnetic material contained in each of the papers, 75 a pawl carried by the handle, and coin-controlled magnetic means for moving the pawl into engagement with any one of the notches whereby movement of the handle moves the frame, thereby withdrawing the 80 paper, the said movement also bringing the papers adjacent the magnet on the frame. 85

17. A vending machine having means for supporting a number of papers therein, a movable rack for moving the papers forwardly as they are successively disposed of, a piece of magnetic material in each paper, movable magnets for co-operation with the magnetic material, together with a chute adapted to receive a coin, the chute 90 being in electrical circuit with a suitable battery and the said magnet, the deposit of the coin therein completing the circuit, and means for moving the magnet. 95

18. A vending machine having means for supporting a number of papers therein, a rack for moving the papers forwardly as they are successively disposed of, a piece of magnetic material in each paper, a frame having a magnet thereon adjacent the 100 papers, a chute adapted to receive a coin, the dropping of the coin in the chute closing an electric circuit through the said magnet, together with means for moving the magnet and also one of the papers by reason 105 of the co-action between the magnet and the piece of magnetic material therein. 110

19. A vending machine having means for supporting a number of papers therein, a rack for moving the papers along as they are successively disposed of, a piece of magnetic material in each paper, a frame having an electro-magnet thereon, the electro-magnet being adjacent that portion of the paper containing the magnetic material, the 115 electro-magnet being in series with a suitable battery, together with a chute adapted to receive a coin, the chute being connected to the said battery, a member adjacent the chute and against which the coin is adapted to engage, the said member being adapted to be placed in circuit with the magnet whereby the circuit through the magnet is closed, together with means for moving the frame whereby the attraction 120 125 130

of the magnet for the magnetic material in the paper will withdraw the paper from the number contained within the machine, and other means also actuated by movement of the handle for moving the papers forwardly.

20. A vending machine comprising suitable means for holding a number of papers in position, a rack for moving the papers forwardly, means for actuating the rack, a piece of magnetic material in each paper, a frame having an electro-magnet thereon, the frame being movable and the magnet being adapted to co-act with the magnetic material in one of the papers in order to withdraw that paper from the rest when the rack is moved, a chute adapted to receive a coin, a movable member adjacent the bottom of the chute with which the coin is adapted to engage, the said movable member and the chute adapted to be placed in circuit with a suitable battery and the afore-mentioned magnet, whereby the dropping of the coin in the chute closes the circuit, a shaft having a notched wheel secured thereto, a handle freely movable adjacent the wheel, a pawl carried by the handle, and electro-magnetic devices actuated by the deposit of the said coin for bringing the handle into engagement with the notched wheel whereby movement of the handle moves the frame in order to withdraw a paper and also actuates the said rack in order to move the other papers forward.
35. 21. A vending machine comprising a stand having a suitable top with an opening therein, a quantity of papers suitably supported in position, a rack for feeding the papers forwardly, a frame having an electro-magnet thereon, a piece of magnetic material positioned in each paper, the electro-magnet being adapted to cooperate with the magnetic material in order to withdraw a paper and bring it adjacent the said opening, whence it will fall outside the machine, a shaft having a notched wheel thereon, a handle freely supported adjacent the shaft, a pawl on the handle, an electro-magnet for moving the pawl into engagement with the notches on the wheel, a chute adapted to receive a coin, a movable member adjacent the chute and with which the coin is adapted to engage, the chute and the movable member being in circuit with the magnet on the handle and being adapted to be placed in circuit with the first magnet on the frame, whereby the magnets are energized and movement of the handle dispenses a paper and moves the remaining papers forwardly into position.

22. A vending machine comprising a stand, the top thereof having a suitable opening, means for holding a quantity of papers in position, a rack against which the

papers rest, a movable frame having a magnet thereon, a piece of magnetic material positioned in each paper, a chain in engagement with the said rack, a plurality of shafts about which the chain turns, a longitudinally extending shaft, the shaft having a notched wheel secured thereto, a handle freely movable adjacent the wheel, a pawl carried by the handle, a magnet adapted to bring the pawl into engagement with any one of the teeth on the wheel, a chute adapted to receive a coin, a movable member adjacent the bottom of the chute and with which the coin is adapted to contact, the magnet on the handle being in circuit with a suitable battery and the said chute and the member adjacent thereto, the magnet on the frame being adapted to be placed in circuit with the chute and the battery whereby when a coin is inserted in place and the handle moved, the shaft with the wheel thereon will be turned, there being connecting means between the handle and the frame whereby the frame is also moved, together with co-operating parts between the first-mentioned shafts and the last-mentioned shaft whereby the rack is moved.

23. In a vending machine, the combination of a shaft having a notched wheel thereon, the said shaft being adapted to actuate the devices within the machine, a handle freely rotatable adjacent the said wheel, a pawl on the handle adapted to engage the notches in the wheel, an electro-magnet for bringing the pawl into engagement with the wheel, a chute adapted to receive a coin, a movable contact adjacent the chute and with which the coin is adapted to contact, the chute and the movable contact, together with the magnet on the handle being in circuit with a suitable battery whereby after a coin is inserted in the chute, downward movement of the handle will turn the notched wheel, there being a pivoted lever with one end of which the handle is adapted to engage, the other end of the lever being adapted to bring the said movable contact remote from the coin whereby the coin is dropped and the circuit is opened.

24. In a vending machine, the combination of a movable handle for actuating the devices therein, a chute adapted to receive a coin, a movable contact adjacent the chute and with which the coin is adapted to contact when it is deposited in the chute, the chute and the movable contact being in circuit with a suitable battery, there being included in the circuit electro-magnetic devices within the machine, together with a pivoted lever, one end of which is adapted to engage with the handle when the same is moved, the other end bringing the movable

- contact away from the chute, thereby permitting the coin to drop and opening the circuit each time the machine is operated.
25. In a vending machine, a pivoted handle a movable lever thereon adapted to engage with an element carried by the machine whereby the elements is actuated, an electro-magnet carried by the handle and adapted to move the lever, a chute adapted to receive a coin, a movable rod having a contact thereon, supported in position adjacent the chute, the contact extending adjacent the bottom of the chute, a downturned portion on the rod, the chute and the contact being in circuit with a suitable battery and the magnet on the handle whereby, when a coin is dropped into a chute it will engage with the said contact whereby it is held in position and the circuit is closed, together with a movable member, the handle being adapted to engage one end thereof after it has traveled a certain distance, the movable member being thereby moved and brought into engagement with a downturned portion of the movable rod whereby the contact thereon is moved remote from the chute and the coin is permitted to drop, thereby opening the circuit.
26. In a vending machine, the combination of a movable handle having a pawl thereon, the pawl being adapted for engagement with certain elements carried by the machine in order to actuate them, an electro-magnet carried by the handle and adapted to actuate the pawl, a chute adapted to receive a coin, a movable rod having a contact thereon positioned adjacent the chute, the contact extending across the bottom thereof, the chute and contact being in circuit with a battery and the said electro-magnet, the coin when in position within the chute closing the said circuit by reason of engagement with the chute and the contact, together with a movable member intermediate of the handle and the said movable rod, the handle being adapted to engage the member after traveling a certain distance whereby a portion of the member comes into engagement with the said rod, thereby moving the contact and permitting the coin to drop and opening the circuit.
27. In a machine of the class described, independent means for supporting a supply of different papers, means adjacent each supply for withdrawing a single paper therefrom, a coin-controlled electric circuit for actuating either of the withdrawing means, together with a plurality of selector rods whereby the circuit is closed through the proper withdrawing means. 55
28. In a machine of the class described, the combination of means for supporting a number of papers in different stacks, electrical devices adjacent each stack for withdrawing a paper therefrom, a coin-controlled electric circuit coöperating with the said electrical devices, together with a plurality of selector rods whereby a selected electric device may be actuated. 60
29. In a machine of the class described, the combination of means for supporting a number of papers in separate stacks, each paper containing a piece of magnetic material, a plurality of electrical devices for withdrawing a paper from either stack, mechanical means for moving the said electric devices, together with a coin-controlled circuit in which the said devices are connected, and selector rods whereby the electric circuit is closed through the proper electric device. 70
30. In a machine of the class described, the combination of independent means for supporting a number of papers in separate stacks, means for moving the stacks forwardly as a paper is withdrawn, each paper containing a piece of magnetic material, a movable frame positioned in the device and carrying magnets adapted to co-act with the magnetic material in the papers, a coin-controlled electric circuit connected to the said devices, together with a plurality of selector rods whereby the circuit through the proper magnet is closed, and mechanical means for moving the frame with the magnets thereon. 85
